WILLIAM N. BARTHOLOMEW, OF NEWTON CENTRE, MASSACHUSETTS,
ASSIGNOR TO JOSEPH RECKENDORFER, OF NEW YORK CITY.

Letters Patent No. 101,344, dated March 29, 1870.

IMPROVEMENT IN PENCIL-CASES.

The Schedule referred to in these Letters Patent and making part of the same

To whom it may concern:

Be it known that I, WILLIAM N. BARTHOLOMEW, of Newton Centre, county of Middlesex and State of Massachusetts, have invented a new and Improved Combined Point-Protector, Extension-Piece, and Lead-Pencil, of which the following is a specification.

Considerable inconvenience is experienced in carrying the ordinary lead-pencil in the pocket. If the pencil be of the usual length it is apt to be in the way, and to project from the pocket, if it be shortened it cannot be conveniently held in the hand and used for any length of time, and at all times the lead point is not only liable to be broken, but also to tear or otherwise injure the pocket.

The object of my invention is to remedy these difficulties, and to this end I combine with a pencil of suitable length, considerably shorter than the ordinary lead-pencil, a tubular stem of metal or other material in which the pencil is inserted, and which will form either an extension piece or a point-protector, as desired. The pencil to be used with this tubular stem is formed so as to have a double taper, that is, to taper toward both ends, so that either end of the pencil when inserted in the stem may be wedged and held securely therein.

The manner in which my invention is or may be carried into effect will be readily understood by reference to the accompanying drawings.

Figures 1, 2, 3, 4 represent central longitudinal sections of the pencil and tubular stem made in accordance with my invention.

In figs. 1 and 2 the double taper to the pencil is formed on the wooden sheath. The greatest diameter of the sheath is at a point, *a*, quite near the head or that end of the pencil which is not intended to be sharpened, and the pencil tapers thence in both directions, thus producing a double tapered head.

The short tapered portion between *a* and *b* is intended to be inserted in the tubular stem *d* when the pencil is required for use, as shown in fig. 1, in which position the combined length of the pencil and stem is quite equal to that of an ordinary pencil, and sufficient to allow the pencil to be easily held between the fingers and supported by the hand.

The longer tapered portion between *a* and *c* is intended to be inserted in the stem when the pencil is no longer required for use, as seen in fig. 2, in which position the pencil is of but little length, being received for the most part in the tubular stem, which now, instead of forming an extension piece, becomes a point-protector.

The tubular stem has an internal diameter about equal to the diameter of the pencil at *a*, so that the

enlarged portion of the wooden sheath will be wedged and held tightly in the tubular stem whichever end be inserted therein.

It will be understood that it is by no means necessary that the pencil should taper continuously between *a* and *b* and *a* and *c*; on the contrary, only such portion of the pencil need be tapered between these points to produce a double incline or taper to fit and wedge in the tube, while the other parts of the pencil may be cylindrical or other ordinary shape.

In figs. 3 and 4 the double taper is formed not upon the sheath itself, but upon a head, *h*, of bone, India rubber, or other material, attached to one end of the pencil in any suitable manner, either fitting upon a tenon, as seen in fig. 3, or being screwed upon the pencil end, as seen in fig. 4. The body of the pencil in this case is of the usual cylindrical or polygonal form.

Instead of using a separate head, *h*, one end of the wooden sheath may be made in the same form, and to answer the same purpose as the head, as I have already indicated.

From the foregoing it will be seen that all that is needed to adapt the pencil for use with the extension and protecting-tube, is that it should be slightly bulging near one end so as to form what I have termed the "double taper," by which the pencil can be firmly held to the tube, whether the point be inserted in the tube for the purpose of protection or withdrawn therefrom and turned outward for use in writing, &c.

Having now described my invention and the manner in which the same is or may be carried into effect, What I claim, and desire to secure by Letters Patent, is—

1. A combined point-protector, extension piece, and lead-pencil consisting of an extension and point-protecting tube in a combination with a lead-pencil furnished at or near one end with a double tapered or inclined head adapted to be wedged and held in the tube whether the point of the pencil be turned out from or inserted in said tube, substantially as shown and set forth.

2. A lead-pencil, the wooden sheath of which is formed with a double taper, so as to admit of the same being wedged and held in the extension and protecting-tube in which either end of the pencil may be inserted, substantially as described.

In testimony whereof I have signed my name to this specification before two subscribing witnesses.

WM. N. BARTHOLOMEW.
